OTHER PUBLICATIONS

Notice of Allowance; Design U.S. Appl. No. 29/484,128, filed Mar. 6, 2014; Blender Container; Date Mailed: Mar. 27, 2015; 7 pages.
(Continued)*Primary Examiner* — Ricky Pham(74) *Attorney, Agent, or Firm* — Cantor Colburn LLP(57) **CLAIM**

We claim, the ornamental design for a blender container, as shown and described.

DESCRIPTIONFIG. 1 is a perspective view of an embodiment of a blender container showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

(Continued)

The broken lines in the drawings are for illustrative purposes only and form no part of the claimed design.

1 Claim, 7 Drawing Sheets
